MAGNETIC WINDOW-CLEANING DEVICE

Rocco D'Andrea, Long Island City, N. Y.

Application May 6, 1949, Serial No. 91,660

6 Claims. (Cl. 15—220)

1

My invention relates to improvements in cleaning devices, and more particularly to a device by means of which the outside of a window pane or other inaccessible surface may be cleaned.

I provide a pair of cleaning elements provided with permanent magnets and adapted to be placed on both sides of a window pane or similar surface to be cleaned. When one cleaning element is rubbed against the inside surface of the pane, the magnetic field causes the other element to move correspondingly. Thus, both surfaces of the window pane may be cleaned simultaneously.

The prior art reveals several attempts to devise cleaning means of this sort. These devices have invariably been limited to the use of portable electro-magnets, which are subject to the following disadvantages: 1. The manufacturing cost of electro-magnets has been too great to enable such cleaning devices to become common household items. 2. The devices were heavy, inconvenient to set up for use, and could only be used on direct current. 3. Cleaning means of this sort could not be used effectively with water.

Up to this time, there has been no evidence of a cleaning device of this type which was provided with permanent magnets, although the use of permanent magnets would enable such devices to be sold at a low cost. This is evidently due to the fact that a device incorporating permanent magnets and made according to the teachings of the prior art could not operate. In the prior devices, the magnet was located inside the window pane, and a pad containing a magnetically-permeable metal was used on the outside of the window pane. The field created by a permanent magnet would therefore be too weak to retain the outside cleaning element against the pane during the cleaning operation. In addition, water or other liquids could not be used effectively with the flat pads provided, since it would tend to form a vacuum between the flat pad and the surface of the window, causing the pad to lag behind the moving inside magnet, so that the pad would invariably fall off the window.

It is the principal object of my invention therefore to provide a cleaning device incorporating permanent magnets which has a novel construction and is made of such material that it can be efficiently and effectively used for cleaning.

Another object of the invention is the provision of a cleaning device of the character described which is made of a few simple and inexpensive parts so that it may be manufactured and sold at a low cost.

Additional objects and advantages of the in-

2

vention are set forth in the following description and drawings which illustrate a preferred embodiment thereof, it being understood that the above statement of the objects of my invention is intended generally to explain the same without limiting it in any manner.

Fig. 1 is a vertical section of the cleaning device of my invention showing the manner in which the cleaning elements thereof are positioned in use against a window pane W.

Fig. 2 is a plan view of the cleaning element which is used to clean the outside surface of a window pane;

Fig. 3 is a section taken along line 3—3 of Fig. 2;

Fig. 4 is an exploded perspective view of the cleaning elements constituting the cleaning device; and

Fig. 5 is a perspective view showing the method by which the cleaning device is operated to clean a window pane.

Referring to the drawings in detail, the cleaning device comprises an inner cleaning element 10 and an outer cleaning element 11. The inner cleaning element 10 is adapted to be used to clean an accessible surface such as the inside surface of a window pane while the outer cleaning element is adapted to clean an inaccessible surface such as the outside surface of a window pane. Figs. 1 and 5 show the relative positions of the elements 10 and 11 when used to clean a window pane W.

The cleaning member 10 comprises a heavy and powerful permanent magnet 13 which is preferably an Alnico magnet or any other type of alloy of similar strength. Said magnet 13 may be of horse-shoe shape as shown in the drawings, or it may be of any other desired shape which will operate as efficiently. Magnet 13 may, for convenience of handling, be housed in a casing 12 which is preferably open at one end. The polar ends of the magnet 13 are aligned with the open end of said casing 12, as shown in Fig. 1.

Casing 12 is made of a magnetically impermeable material such as copper, brass, wood, plastic, or the like, so that it will not shunt, or otherwise interfere with the field of the magnet 13. Magnet 13 is preferably press-fit within casing 12 although it may also be adhesively secured, or attached in any other suitable manner.

Casing 12 is preferably provided with an enlarged end portion 12a which serves as a handle or gripping portion of cleaning element 10.

Cleaning element 10 is also provided with a trough-shaped cleaning pad or cloth 14 which is shaped to fit snugly over the open end of casing 12. Pad 14 is preferably made of a piece of 60 thick woolen fabric which is stitched together

at its sides to form upstanding walls 14a. The walls 14a fit snugly against the side walls of casing 12, adjacent the open ends thereof, so that the pad 14 may be readily removed and replaced. The pad 14 may be made in any other suitable shape, however, and may be attached over the open end of casing 12 in any suitable manner. For instance, a woolen bag may be provided which completely encloses the casing 12, or encloses the magnet 13 without any casing.

The cleaning member 11 comprises a rectangular pouch 15 which is provided with a plurality of pockets 16, each of said pockets containing a small permanent magnet 17. The pouch 15 is made of a heavy woolen material. For economy of manufacture, I prefer to use a single piece of wool fabric folded in half and closed along its edges by marginal rows of stitching 18. The pockets 16 can be made simply by providing longitudinal rows of stitching 19 which are preferably equally spaced. In the drawings, the pouch 15 is shown with three such pockets 16, but it is to be understood that any number of pockets may be provided, depending on the size of the cleaning member 11 and the size of the magnets 17 to be contained therein.

The magnets 17 are preferably Alnico cylindrical bar-magnets having a diameter of $\frac{1}{4}$ inch. These magnets are light, but have a strong magnetic field. Pockets 16 of pouch 15 are of such a size that each magnet 17 is snugly housed within its respective pocket, being held in a parallel, spaced relationship to the other magnets 17. Said magnets are inserted within their respective pockets with like poles adjacent one another, so that the north-seeking poles of magnets 17 are aligned at one end of pouch 15, while the south-seeking poles are aligned at the other end thereof.

In use, the cleaning member 11 is pressed against the outside of a window pane W, or similar surface to be cleaned, and the cleaning member 10 is pressed against the inside of the window pane, with the cleaning pad 14 abutting said window pane, and in register with cleaning member 11. The south-seeking pole of magnet 13 is aligned opposite the north-seeking poles of magnets 17, so that the magnetic field between said poles retains cleaning member 11 firmly pressed against the window pane W. When cleaning member 10 is slid along the window pane in any direction, this magnetic field, passing through said window pane, will cause cleaning member 11 to follow. As cleaning member 10, therefore, is rubbed over the entire inner surface of the window pane, cleaning member 11 will also move over the entire outer surface of the window pane. Both surfaces of said window pane may thus be cleaned simultaneously.

It is to be noted that the length and width of the cleaning elements 10 and 11 are preferably equal, so that said elements may be aligned in registering position with the poles of their respective magnets also in alignment. The depth of cleaning element 10 is, however, appreciably greater than the depth of cleaning element 11, said cleaning element 10 being thus adapted to contain a large and powerful permanent magnet. The cleaning element 11 is, on the other hand, relatively flat, and the magnets 17 contained therein are small in size, so that said cleaning element 11 is light enough to be retained against the window pane and to be easily moved.

In actual use, I prefer to use a pair of cleaning pads or cloths 14, and a pair of cleaning elements 11. One of said cleaning pads 12 is slipped

over the end of casing 12 and is dipped in a suitable cleaning preparation such as glass-cleaning wax. One of the cleaning elements 11 is also dipped in the wax. The cleaning elements 10 and 11 are applied to their respective surfaces of the window pane W, and the wax may be distributed over both surfaces of the window pane as shown at L in Fig. 5 by moving the inside cleaning element 10 over the surface of the window pane. After a coating of wax has been applied to the entire window pane, the wax-impregnated pad 14 is slipped off the casing 12, and is replaced by the dry pad. The dry cleaning element 11 is also substituted for the wax-impregnated element, and the cleaning elements 10 and 11 are again used in a similar manner to wipe the wax coating from the window pane.

The pad 14 and the pouch are made of a heavy woolen fabric since I have found that best operating results are afforded by this material. Wool fabric absorbs and holds a large amount of cleaning wax and enables the wax to pass readily to that portion of the fabric which abuts the window pane. The woolen fabric also has an affinity for sliding over the surface of the window pane without sticking.

I prefer to use a liquid wax cleaning composition, since, as was previously indicated, the use of water tends to create a vacuum between the outer cleaning element and the surface of the window. Liquid wax, however, may be easily distributed over the window pane surface in a thin coating and does not have this tendency to cause the outside cleaning element to stick or move sluggishly. Furthermore, the liquid wax does not cause rusting of the magnets contained in the cleaning elements, as is the case with water.

To prevent any possibility of creating a vacuum should the cleaning element 11 be too heavily saturated with wax, I use several small magnets in the cleaning element 11 instead of one large magnet. Since these magnets 17 are snugly contained in the pockets 16, each pocket 16 presents an outwardly protruding surface or bulge. Between these bulges are longitudinal grooves or depressions 20, at the center of which the longitudinal rows of stitching 19 are located, as shown in Fig. 3. When the cleaning element 11 is held firmly against the window pane by the magnetic lines of force, it will be readily seen that only the bulging surfaces of the pouch 15 will abut said window pane. Since air can circulate through the longitudinal depressions or grooves 20, no vacuum can be formed between the window pane and the cleaning element 11. If desired, a single, flat bar-magnet may be employed and the bulges and depressions provided in pouch 15 by padding the walls of said pouch. The same result may be obtained by using a magnet provided with alternate ridges and channels.

The use of magnets in both cleaning elements 10 and 11 provides a magnetic field which is sufficiently strong for effective operation, even though said cleaning elements are spaced from each other. To prevent the outside cleaning element 11 from accidentally dropping off the window pane and possibly injuring passers-by, a string 21 may be attached to one end of said cleaning element. The other end of the string may be attached to the cleaning member 10, or to an object inside the room, or may merely be held by the user.

To insure the proper alignment of the poles of magnets 13 and 17, the cleaning elements 10 and

11 may be marked with suitable indicia to indicate opposite poles of said magnets.

The cleaning elements 10 and 11 are made rectangular in shape so that they may clean the corners of the window pane.

While a preferred embodiment of the invention has been shown and described herein, it is obvious that numerous additions, changes, and alterations may be made in the invention without departing from the spirit and scope thereof. For instance, the cleaning pouch 15 and the cleaning pad 14 may be made of a chemically-treated material which is used for cleaning purposes and to which no water or other cleaning agent need be added.

I claim:

1. For use in cleaning a window pane, a cleaning device which comprises a first cleaning element and a second cleaning element, said first cleaning element having a permanent magnet, and a liquid-impregnable covering for said magnet, said first cleaning element being adapted to be held against said window pane with the covering abutting the inner surface of said window pane and the poles of said magnet proximate to said window pane, said second cleaning element comprising a pouch-like covering made of a liquid impregnable material, and at least one permanent magnet housed in said covering, said second cleaning element being adapted to be oriented against the outer surface of said window pane with the poles of the contained magnet oppositely aligned with the poles of the magnet of said first cleaning element, the wall of said pouch-like covering adjacent said window pane having protruding portions which abut said window pane, and depressions between said protruding portions, said magnets having a sufficiently strong field and the second cleaning element being sufficiently light in weight to enable said second cleaning element in its oriented position to be held firmly against the outer surface of the window pane by said magnetic field and to follow the movement of said first cleaning element against said window pane.

2. A cleaning device according to claim 1 in which the pouch-like covering of the second cleaning element is made of a woolen fabric material.

3. For use in cleaning a window pane, a cleaning device which comprises a first cleaning element and a second cleaning element, said first cleaning element having a permanent magnet, and a liquid-impregnable covering for said magnet, said first cleaning element being adapted to be held against said window pane with the covering abutting the inner surface of said window pane and the poles of said magnet proximate to said window pane, said second cleaning element comprising a pouch-like covering member made of a liquid-impregnable material and having a plurality of pockets arranged substantially parallel to each other, and a permanent bar-magnet housed in each of said pockets, said bar-magnets being held within said pockets with the north-seeking poles thereof aligned at one end of the covering member, said second cleaning element being adapted to be oriented against the outer surface of the window pane with the poles of its contained magnets oppositely aligned with the poles of the first cleaning element magnet, said pockets being of such a size that the contained magnets cause the wall of said covering member to bulge adjacent the center of each pocket, and

to form a depression between said pockets, said depressions running from one end of the covering member to the other, said magnets having a sufficiently strong field and the second cleaning element being sufficiently light in weight to enable said second cleaning element in its oriented position to be held firmly against the inner surface of the window pane by said magnetic field, and to follow the movement of said first cleaning element against said window pane.

4. A cleaning device according to claim 3 in which the pouch-like covering member of the second cleaning element is made of a woolen fabric material.

5. For use in cleaning a window pane, a cleaning device which comprises a first cleaning element and a second cleaning element, said first cleaning element having a permanent magnet, a casing enclosing said magnet, and a trough-shaped cleaning pad removably secured over that end of said casing adjacent both poles of said magnet, said first cleaning element being adapted to be held against said window pane with the cleaning pad abutting the inner surface of the window pane and the poles of the magnet proximate to said inner surface, said second cleaning element comprising a closed, pouch-like covering member made of a liquid impregnable material and having a series of longitudinally-disposed parallel pockets which extend the length of said covering member, and a permanent bar-magnet filling each of said pockets, said bar-magnets being disposed within said pockets with the north-seeking holes thereof aligned at one end of said covering member, said second cleaning element being adapted to be oriented against the outer surface of said window pane with the poles of its contained magnets oppositely aligned with the respective poles of the first cleaning element, the magnets of said second cleaning element of sufficient diameter to cause the outer wall of said covering member to present longitudinal bulging portions over said pockets, said covering member having longitudinally disposed depressions between said pockets, said bulging portions abutting the window pane surface in the oriented position of said second cleaning element, said magnets having a sufficiently strong field and the second cleaning element being sufficiently light in weight to enable said second cleaning element in its oriented position to be held firmly against the inner surface of the window pane by said magnetic field, and to follow the movement of said first cleaning element against said window pane.

6. A cleaning device according to claim 5 in which the pouch-like covering member of the second cleaning element is made of a woolen fabric material.
